CATALYTIC CONVERSION OF HYDROCARBONS IN THE PRESENCE OF REGENERATION GASES

Percival C. Keith, Peapack, N. J., assignor to Hydrocarbon Research, Inc., New York, N. Y., a corporation of New Jersey

Application January 20, 1950, Serial No. 139,758

8 Claims. (Cl. 196—52)

1

This application is a continuation-in-part of the copending application, Serial No. 723,345, filed January 21, 1947, now issued as U. S. Patent 2,495,262.

The present invention relates to the high-temperature treatment of hydrocarbons wherein a bed of comminuted contact material is alternately contacted by the hydrocarbons which are to be converted and by an oxygen-containing gas to burn off the carbonaceous matter deposited on the contact material by the hydrocarbons undergoing conversion.

In general, prior processes of the type contemplated by this invention have been characterized by discontinuous operation inasmuch as the hydrocarbon stream is passed in contact with the contact material until an objectionable quantity of carbonaceous matter is deposited on the contact material, the flow of the hydrocarbon stream is then discontinued, and the carbonaceous matter is removed from the contact material by burning with a stream of oxygen-containing gas passed in contact therewith. Furthermore, it is customary to discard the gases resulting from the regeneration of the contact material since the gases generated in these prior processes have little or no practical value. It follows, therefore, that the portion of the hydrocarbon feed which goes into the formation of the carbonaceous deposit on the contact material is ultimately lost by combustion which yields a valueless flue gas.

Principal objects of this invention include the provision of a simplified process for the high-temperature treatment of hydrocarbons which is substantially continuous in operation in spite of the fact that contact material employed in the process is alternately used in the treatment of the hydrocarbons and subjected to regeneration to remove carbon therefrom, and the provision of processing conditions which avoid the wasteful consumption of carbon in the production of flue gas and lead to increased yields to valuable hydrocarbon products.

These and other objects and advantages of the invention will be apparent from the description which follows.

To avoid verbiage, the term, catalyst, will be hereinafter used in lieu of contact material. It is, of course, known that various contact materials have different propensities or activities for facilitating the conversion of hydrocarbons at elevated temperatures. However, all contact materials in solid particle form as employed in the present invention have in common the function of presenting large surface areas to the hy-

2

drocarbons during their passage through the treatment or conversion zone. Accordingly, the term, catalyst, is herein used in its broadest sense to connote any particulate material presenting a large surface area to hydrocarbons undergoing conversion in order to facilitate the conversion and to hold the carbon formed during the conversion.

In accordance with this invention, the hydrocarbon stream which is to be subjected to high-temperature treatment or conversion is injected at an intermediate point in a mass of particulate catalyst disposed in the form of a plurality of serially connected beds while a regenerating gas consisting essentially of oxygen and steam is injected into the catalyst mass at a point closer to one of the two extreme ends of the series of catalyst beds so as to regenerate the catalyst mass in the vicinity of the point of introduction of the regenerating gas and to effect the concurrent flow of the resulting regeneration gases and the hydrocarbon stream from the point of introduction of the hydrocarbon stream toward the other extreme end of the series of catalyst beds. Periodically, the hydrocarbon stream is made to flow from its point of introduction into the catalyst mass concurrently with the regeneration gases toward the extreme end of the series of catalyst beds opposite the end toward which it was previously flowing by shifting the point of injection of the regenerating gas closer to the extreme end toward which the hydrocarbon stream was previously flowing. Thus, for the sake of simplicity and further clarification, if the catalyst mass is arranged in two serially connected beds of equal volume, the hydrocarbon stream is introduced at the point of juncture of the two beds, intermediate the two extreme ends of the serially connected beds while the regenerating gas is injected into one of the two extreme ends and made to flow toward the opposite extreme end where a mixture of the regeneration gases and the treated or converted hydrocarbon stream is withdrawn; periodically, the regenerating gas is injected into the extreme end of the serially connected catalyst beds from which the mixture of regeneration gases and converted hydrocarbon stream was previously withdrawn so that the resulting regeneration gases make the hydrocarbon stream flow from the intermediate point of its introduction toward the extreme end of the serially connected catalyst beds into which the regenerating gas was previously injected.

55 Improvements in the quantity and quality of

the hydrocarbon conversion products are achieved by this invention through the coupling of the inherent benefits arising from the conversion of hydrocarbons by the processing procedure provided by the present invention with the selection of particular processing conditions, especially the composition of the regenerating gas, and operating temperatures and pressure.

A fundamental aspect of this invention is the discovery that under selected processing conditions, the production of nonvolatile carbonaceous matter or coke is materially suppressed by the hydrogen-containing regeneration gases which become commingled with the hydrocarbon stream undergoing treatment. This advantage is increasingly more evident with increasingly heavier charging oil stocks. Thus, while a naphtha fraction may be beneficially treated by the process of this invention, it is in the conversion of heavy oils, like topped or reduced crude petroleum, that the greatest benefits are realized. It has been found that the suppression of carbon formation is achieved to a material extent when the partial pressure of the hydrogen within the hydrocarbon conversion zone is at least about 75 p. s. i. (pounds per square inch) and preferably at least about 100 p. s. i. It is curious to note that maximum benefits from the presence of hydrogen generally occur at hydrogen partial pressure not exceeding about 200 p. s. i. so that there is little or no justification in seeking a hydrogen partial pressure greater than about 200 p. s. i.

To obtain the desired hydrogen partial pressure in the hydrocarbon conversion zone, the whole reaction system is maintained at a pressure in the range of about 200 to 800 p. s. i. g. (pounds per square inch gauge), preferably in the range of about 300 to 650 p. s. i. g., and the carbon deposit on the catalyst particles is removed therefrom by reaction with a regenerating gas consisting essentially of a preponderance of steam and a minor proportion of high-purity oxygen under conditions favoring the production of hydrogen in the regeneration zone. More specifically, the high-purity oxygen may be the product of air liquefaction and rectification containing at least about 90% by volume of oxygen, preferably at least about 95% by volume of oxygen.

The principal reactions by which the carbon deposit is eliminated from the catalyst particles include:

Another important reaction taking place in the regeneration zone is the water-gas shift reaction:

Reactions A, B and E are exothermic while reactions C and D are endothermic. Reactions D and E produce the hydrogen employed by this invention in improving the hydrocarbon conversion step. The regenerating gas contains an excess of steam or water vapor over oxygen to ensure maximum yield of hydrogen. From the viewpoint of stoichiometry, a regenerating gas comprising about 2 volumes of water vapor for each volume of oxygen would have an adequate proportion of water vapor to assure a high yield of hydrogen in the regeneration product gases.

However, as a practical matter, since the temperature of the catalyst particles and the materials of construction of the reactor generally must be kept below 3000° F. to avoid fusion or other injury, it is necessary to employ a considerably larger steam-to-oxygen ratio, at least of the order of 3:1. Refractory materials like zirconia from which the catalyst particles and reactor lining can be made to withstand elevated temperatures ranging up to about 3000° F. are fairly expensive and, therefore, it is frequently advisable to choose from the cheaper refractories which usually can withstand temperatures not exceeding about 2500° F. Steam-to-oxygen ratios in the range of about 3:1 to 7:1 are generally satisfactory for maintaining the regeneration temperature in the desirable range of about 1600° to 2500° F. For the purposes of this invention which depends upon an appreciable production of hydrogen during the regeneration of the catalyst, the regeneration temperature must not be permitted to fall below about 1400° F. In short, it is advisable to conduct the regeneration at temperatures approaching the maximum temperature permissible with the chosen catalyst particles and reactor materials, and this means in turn, that the regenerating gas should have the smallest steam-to-oxygen ratio which will afford the necessary temperature control. In most instances, regeneration is carried out at temperatures in the range of substantially 1600° to 2500° F. with regenerating gases having steam-to-oxygen ratios in the range of substantially 3:1 to 7:1.

The beneficial influence of the regeneration product gases which contain a material proportion of hydrogen and which become commingled with the hydrocarbon stream in the conversion zone is principally attained when the conversion zone is maintained at temperatures in the range of about 800° to 1050° F. Optimum conversion results are generally obtained at temperatures in the range of about 850° to 950° F.

To attain desired reforming or conversion of heavy oil molecules, it is necessary to maintain a substantial partial pressure of oil, usually about 40 to 90 p. s. i. in the conversion zone. Such a substantial oil partial pressure is ensured by operating the reaction system at an elevated pressure in the range of about 200 to 800 p. s. i. g.

It is highly advisable to preheat all of the reactants entering the reaction system to the highest practical temperatures approaching the respective reaction temperatures of these reactants.

For instance, since the regeneration zone is operated at temperatures of not less than about 1400° F., the regenerating gas is usually charged at temperatures in the vicinity of 1000° F.; specifically, steam may be supplied at a temperature of about 900° to 1100° F. along with high-purity oxygen preheated to a temperature of about 400° to 800° F. With the conversion zone operating at temperatures of not less than about 800° F., it is desirable to preheat the hydrocarbon stream to a temperature as close to the conversion temperature as is possible without causing coking or other hydrocarbon degradation in the preheater. Most hydrocarbon feed stocks can be safely preheated to temperatures in the range of 600° to 750° F.

Suitable contact materials or catalysts include quartz chips, alumina, magnesia, zircon, beryl and bauxite. It is clear that the catalyst should be selected on the basis of its ability to withstand the desired regeneration conditions includ-

ing a temperature of not less than about 1400° F. without physically disintegrating or fusing.

For a clearer and more detailed understanding of this invention, reference is now made to the drawing forming a part of this specification and showing diagrammatically one preferred form of apparatus suitable for carrying out the process of this invention.

The reaction system comprises a vertically elongated reactor 10 having opposed extremities 11 and 12 and provided internally with a plurality of catalyst beds 13. Each catalyst bed 13 is held in place in reactor 10 by a lower foraminous member or perforated plate 14 and an upper foraminous member or perforated plate 15. To facilitate the introduction of the reactants, the serially disposed catalyst beds 13 are preferably spaced so as to leave a distributing zone 16 between each pair of contiguous beds 13.

The hydrocarbon feed stock is supplied by line 17 to a preheating furnace 18 whence it is conveyed by line 19 to the middle of elongated reactor 10. The charged hydrocarbon stream flows through reactor 10 from the mid-point of introduction either upwardly to extremity 11 or downwardly to extremity 12 depending upon whether the regenerating gas is introduced into the lower extremity 12 or into the upper extremity 11, respectively.

The regenerating gas consisting essentially of a preponderance of steam and a minor proportion of high-purity oxygen is supplied by line 20 having an upper branch line 21 extending to line 22 connected to upper extremity 11 and a lower branch line 23 extending to line 24 connected to lower extremity 12. Upper branch line 21 is provided with a valve 25 while lower branch line 23 is provided with a valve 26. During one period or cycle of operation the regenerating gas is made to flow into lower extremity 12 of reactor 10 by closing valve 25 and opening valve 26. Under these conditions, carbonaceous matter deposited in the catalyst beds 13 of the lower half of reactor 10 during the preceding period or cycle of operation is eliminated from these beds by reaction with the regenerating gas entering extremity 12 and flowing upwardly to meet the hydrocarbon stream supplied to the mid-point of reactor 10. Thence, the commingled hydrocarbon stream and regeneration product gases containing hydrogen continue to flow upwardly through the catalyst beds 13 of the upper half of reactor 10 under conditions promoting the desired conversion of the hydrocarbon stream. The treated or converted hydrocarbon stream admixed with the regeneration gases leaves extremity 11 of reactor 10 by way of line 22 which discharges into line 27 which, in turn, conveys the total reaction effluent to a suitable separation plant wherein this reaction effluent is separated into desired product fractions. It will be appreciated that in addition to liquid hydrocarbon fractions like gasoline, there is recovered from the total reaction effluent a normally gaseous fraction which is valuable in view of its high heating value and its suitability for use in other chemical reactions, particularly the catalytic synthesis of hydrocarbons and oxygenated hydrocarbons from hydrogen and carbon monoxide. Line 22 is provided with a valve 28 which is opened when the reaction effluent is passing from upper extremity 11 of reactor 10 through line 22; at the same time, valve 29 in line 24 is kept closed.

In the next period or cycle of operation the regenerating gas is made to flow through upper

branch line 21 by closing valve 26 and opening valve 25. Similarly, valve 28 is closed and valve 29 is opened. Under these circumstances, the regenerating gas enters upper extremity 11 and flows downwardly through catalyst beds 13 in the upper half of reactor 10 to effect the removal of carbonaceous matter laid down therein during the preceding cycle of operation by the hydrocarbon stream undergoing conversion; the regeneration product gases become commingled with the hydrocarbon stream entering the mid-point of reactor 10 and continue to flow downwardly under hydrocarbon conversion conditions through catalyst beds 13 in the lower half of reactor 10. The total reaction effluent leaves lower extremity 12 by way of line 24 connected to line 27 which conveys the reaction effluent to the separation plant. When this cycle of operation reaches the point where it becomes necessary to regenerate catalyst beds 13 in the lower half of reactor 10, the first-described cycle is repeated by closing valves 25 and 29 and opening valves 26 and 28. Again, when the catalyst beds 13 of the upper half of reactor 10 require regeneration, the introduction of regenerating gas is shifted from the lower extremity 12 to upper extremity 11 by opening valves 25 and 29 and closing valves 26 and 28.

It is clear from the foregoing description that through the simple alternation of the point of introduction of the regenerating gas the hydrocarbon stream changes its direction of flow from spent or fouled catalyst beds to regenerated catalyst beds without necessitating any interruption in the charging of the hydrocarbon stream to reactor 10. In other words, the hydrocarbon feed stock passing through line 17, preheater 18 and line 19 may flow continuously at a desired, uniform rate without regard to its changing direction of flow through reactor 10 as necessitated by the periodic regeneration of the several catalyst beds 13.

With the heavier hydrocarbon feed stocks, a sufficient quantity of carbonaceous matter will be laid down on the catalyst during the conversion cycle to ensure an adequate production of hydrogen during the regeneration cycle so that the commingled regeneration product gases and the hydrocarbon feed stream will have a hydrogen partial pressure of at least about 75 p. s. i. and preferably at least about 100 p. s. i. However, when such a hydrogen partial pressure cannot be obtained because of a deficiency of carbon laid down on the catalyst by the hydrocarbon feed during conversion, the desired hydrogen partial pressure can be attained by supplementing the hydrogen formed during regeneration in the reactor with hydrogen separated from the total reaction effluent and recycled to the reactor. In such case, there is separated from the total reaction effluent a gaseous fraction which is rich in hydrogen and this fraction is recycled to the reactor. As shown in the drawing, the hydrogen-containing fraction may be recycled by line 30 which is connected with hydrocarbon feed line 17. If desired, a portion or all of the recycled gas may be diverted through line 31 connected to line 19. Similarly, for flexibility and control of process conditions, a portion of the hydrocarbon stream may by-pass preheater 18 by way of line 32 which extends from line 17 to line 19.

Other possible modifications of the reaction system are shown in the drawing. For instance, branch line 21 may be provided with valved branches 33 for injecting the regenerating gas

into each of the distributing zones 16 in the upper half of reactor 10 when the catalyst is being regenerated in this portion of reactor 10 and, likewise, branch line 23 may be provided with valved branches 34 to supply the regenerating gas individually to the catalyst beds 13 in the lower half of reactor 10 during the next cycle of operation. When the regenerating gas is being charged into the upper portion of reactor 10, the gas may be evenly divided for simultaneous passage through open valves 25 and 33. Alternatively, most or all of the gas may at first pass through valve 25 and gradually the gas flow may be shifted to the uppermost valve 33, then to the next lower valve 33, and so on; in the next cycle of operation, most or all of the gas at first flows through valve 26 and gradually the gas flow is shifted to the lowermost valve 34, then to the next higher valve 34, and so on. Similarly, line 19 may have upper valved branches 35 and lower valved branches 36. Thus, it is possible to divide the hydrocarbon feed stream evenly for injection into each of the catalyst beds 13 in the upper half of reactor 10 during one cycle of operation and into each of the catalyst beds 13 in the lower half of reactor 10 during the next cycle of operation. Also, the hydrocarbon stream may at first flow directly from line 19 to the middle of reactor 10 and, in the course of the cycle when regeneration is being carried out in the lower half of reactor 10, the hydrocarbon flow may be shifted to the lowermost branch 35, then to the next higher branch 35, and so on. In the succeeding cycle when regeneration is carried out in the upper half of reactor 10, the hydrocarbon flow is shifted from the uppermost branch 35 back to the middle of reactor 10 and, during this cycle, the hydrocarbon flow is gradually shifted to the uppermost branch 36, then to the next lower branch 36, and so on. When the next cycle of regeneration in the lower half of reactor 10 is initiated, the flow of hydrocarbon is transferred from the lowermost branch 36 back to the middle of reactor 10 by direct injection through line 19 and the flow sequence just described is repeated.

Through still another simple modification, it is possible to strip with steam adsorbed hydrocarbons from fouled catalyst before it is subjected to regeneration and, likewise, to strip with steam adsorbed oxygen from regenerated catalyst before hydrocarbons are brought into contact therewith. As shown in the drawing, the supply end of line 20 has a branch 20A through which steam is fed and a branch 20B provided with valve 20C for supplying high-purity oxygen. Thus, when it is desired to strip the catalyst with steam between each alternation from a conversion cycle to a regeneration cycle and vice versa, the supply of oxygen may be momentarily interrupted by closing valve 20C. For instance, assuming that the switching from the conversion cycle to the regeneration cycle is made every 16 minutes, valve 20C may be closed for the first minute of the 16-minute period so that steam alone passes through the portion of the catalyst to be regenerated in order to purge or strip hydrocarbons therefrom, valve 20C may then be opened for 14 minutes to effect oxidative regeneration of the catalyst, and for the last minute of the 16-minute period valve 20C may again be closed so that the continuing flow of steam urges the regenerated catalyst of residual oxygen just before the hydrocarbon stream is made to flow in con-

tact with the regenerated catalyst in the succeeding 16-minute period.

It is seen from the foregoing illustrative modifications that through the simple manipulation of valves various flow sequences of the reactants entering the reactor can be achieved to afford greater flexibility and control of the process conditions.

As a specific example of the invention, East Texas Black oil having 14° API gravity is treated in a reactor as shown in the drawing containing beds of approximately $\frac{1}{2}$ -inch diameter pellets prepared from alumina gel. With an oil charging rate of 10,000 barrels per day, oxygen of 95% by volume purity is supplied at the rate of 4.23 millions of cubic feet (standard conditions) per day together with 950,000 lbs. per day of steam as the regenerating gas (steam-to-oxygen ratio of 5:1). The oil is preheated to a temperature of 700° F., the oxygen to 450° F. and the steam to 1000° F. The total depth of contact pellets in the reactor is about 30 feet and the reactor is 15 feet in diameter. A gauge pressure of 600 p. s. i. is maintained in the reactor, the hydrogen partial pressure being 180 p. s. i. The average temperatures in the regeneration and conversion zones are about 1900° F. and 940° F., respectively. The switching between conversion and regeneration zones is made every 25 minutes. From the total reaction effluent, there are recovered each day the following liquid products:

	API Gravity	Barrels
35		
Gasoline (C ⁴ and higher hydrocarbons boiling up to 400° F.)	55°	4,500
Gas Oil (boiling 400° to 700° F.)	33°	2,300
Heavy Distillate (boiling 700° F. and higher)	15°	1,900
40	Total Liquid Hydrocarbons	8,700

The rest of the charged oil is recovered in the form of fuel gas (approximately 25 millions of standard cubic feet per day) having a heating value of about 430 B. t. u. per standard cubic foot. The gasoline thus produced has an ASTM motor octane number of 78.

In view of the various modifications of the invention which will occur to those skilled in the art upon consideration of the foregoing disclosure without departing from the spirit or scope thereof, only such limitations should be imposed as are indicated by the appended claims.

What I claim is:

55. 1. The process of treating hydrocarbons by passage through a mass of catalyst wherein carbonaceous matter is deposited by said hydrocarbons during passage therethrough and periodically said carbonaceous matter is removed by a regenerating gas, which comprises maintaining said mass at a pressure of about 300 to 650 p. s. i. g., supplying to said mass in the vicinity of one end thereof a regenerating gas consisting essentially of steam and oxygen of at least about 60 95% by volume purity in the respective molar proportions of about 3:1 to 7:1 to effect removal of said carbonaceous matter by conversion at a temperature of about 1600° to 2500° F. to a regeneration product gas consisting predominantly 65 of hydrogen and carbon monoxide, flowing said product gas through said mass toward the opposite end thereof and simultaneously injecting said hydrocarbons into said product gas at a point in said mass intermediate said ends, maintaining a temperature of about 850° to 950° F. and 70 75

a hydrogen partial pressure of about 100 to 200 p. s. i. in the resulting mixture of said product gas and said hydrocarbons, withdrawing said mixture from said mass in the vicinity of said opposite end, and periodically reversing the flow of said mixture through said mass by supplying said regenerating gas in the vicinity of said opposite end and withdrawing said mixture in the vicinity of the first said end.

2. The process of converting heavy hydrocarbons of the type of topped petroleum crude oil principally to high-quality gasoline by passage of said hydrocarbons through a mass of catalyst wherein carbonaceous matter is deposited by said hydrocarbons during passage therethrough and periodically said carbonaceous matter is removed by a regenerating gas, which comprises maintaining said mass at a pressure of about 200 to 800 p. s. i. g., supplying to said mass in the vicinity of one end thereof a regenerating gas consisting essentially of steam and oxygen of at least about 90% by volume purity in the respective molar proportions of about 3:1 to 7:1 to effect removal of said carbonaceous matter by conversion at a temperature of about 1600° to 2500° F. to a regeneration product gas consisting predominantly of hydrogen and carbon monoxide, flowing said product gas through said mass toward the opposite end thereof and simultaneously injecting said hydrocarbons into said product gas at a point in said mass intermediate said ends, maintaining a temperature of about 850° to 950° F. and a hydrogen partial pressure of about 100 to 200 p. s. i. in the resulting mixture of said product gas and said hydrocarbons, withdrawing said mixture from said mass in the vicinity of said opposite end, recovering from the withdrawn mixture high-quality gasoline as the principal product of conversion of said hydrocarbons, and periodically reversing the flow of said mixture through said mass by supplying said regenerating gas in the vicinity of said opposite end and withdrawing said mixture in the vicinity of the first said end.

3. The process of converting hydrocarbons by passage through a mass of catalyst wherein carbonaceous matter is deposited by said hydrocarbons during passage therethrough and periodically said carbonaceous matter is removed by a regenerating gas, which comprises maintaining said mass at a pressure of about 200 to 800 p. s. i. g. in fluid-communicating conversion and regeneration zones, supplying to said regeneration zone regenerating gas consisting essentially of steam and oxygen of at least about 90% by volume purity in the respective molar proportions of about 3:1 to 7:1 to effect removal of said carbonaceous matter by conversion at a temperature of about 1600° to 2500° F. to a regeneration product gas consisting predominantly of hydrogen and carbon monoxide, flowing said product gas through said conversion zone and simultaneously injecting said hydrocarbons into said product gas, maintaining a temperature of about 800° to 1050° F. and a hydrogen partial pressure of about 100 to 200 p. s. i. in the resulting mixture of said product gas and said hydrocarbons in said conversion zone, withdrawing said mixture from said conversion zone, and periodically switching said conversion and regeneration zones by supplying said regenerating gas to the aforesaid conversion zone and withdrawing said mixture from the aforesaid regeneration zone.

4. The process of converting hydrocarbons by passage through a mass of catalyst wherein car-

bonaceous matter is deposited by said hydrocarbons during passage therethrough and said carbonaceous matter is subsequently removed by a regenerating gas, which comprises maintaining said mass at a pressure of about 200 to 800 p. s. i. g. in fluid-communicating conversion and regeneration zones, supplying to said mass in said regeneration zone a regenerating gas consisting essentially of steam and oxygen of at least about 90% by volume purity in the respective molar proportions of about 3:1 to 7:1 to effect removal of said carbonaceous matter by conversion at a temperature of about 1600° to 2500° F. to a regeneration product gas consisting predominantly of hydrogen and carbon monoxide, flowing said product gas through said mass in said conversion zone and simultaneously and continuously injecting said hydrocarbons into said product gas while said product gas is flowing through said conversion zone, maintaining a temperature of about 800° to 1050° F. and a hydrogen partial pressure of 75 to 200 p. s. i. in the resulting mixture of said product gas and said hydrocarbons, withdrawing said mixture from said conversion zone, and subsequently subjecting said mass in said conversion zone to the action of said regenerating gas and said mass in said regeneration zone to the action of said mixture of regeneration product gas and hydrocarbons.

5. The process of converting heavy hydrocarbons of the type of topped petroleum crude oil by passage through a mass of catalyst wherein carbonaceous matter is deposited by said hydrocarbons during passage therethrough and said carbonaceous matter is subsequently removed by a regenerating gas, which comprises maintaining said mass at a pressure of about 300 to 650 p. s. i. g. in fluid-communicating conversion and regeneration zones, supplying to said mass in said regeneration zone a regenerating gas consisting essentially of steam and oxygen of at least about 90% by volume purity in the respective molar proportions of about 3:1 to 7:1 to effect removal of said carbonaceous matter by conversion at a temperature of about 1600° to 2500° F. to a regeneration product gas consisting predominantly of hydrogen and carbon monoxide, flowing said product gas through said mass in said conversion zone and simultaneously and continuously injecting said hydrocarbons into said product gas while said product gas is flowing through said conversion zone, maintaining a temperature of about 800° to 1050° F. and a hydrogen partial pressure of about 100 to 200 p. s. i. in the resulting mixture of said product gas and said hydrocarbons, withdrawing said mixture from said conversion zone, and subsequently subjecting said mass in said conversion zone to the action of said regenerating gas and said mass in said regeneration zone to the action of said mixture of regeneration product gas and hydrocarbons.

6. The process of converting hydrocarbons by passage through a mass of catalyst wherein carbonaceous matter is deposited by said hydrocarbons during passage therethrough and said carbonaceous matter is subsequently removed by a regenerating gas, which comprises maintaining said mass at a pressure of about 200 to 800 p. s. i. g. in fluid-communicating conversion and regeneration zones, supplying to said mass in said regeneration zone a regenerating gas consisting essentially of steam and oxygen of at least about 90% by volume purity in the respective molar proportions of about 3:1 to 7:1 to effect removal of said carbonaceous matter by conversion

at a temperature of about 1600° to 2500° F. to a regeneration product gas consisting predominantly of hydrogen and carbon monoxide, flowing said product gas through said mass in said conversion zone and simultaneously and continuously injecting said hydrocarbons into said product gas while said product gas is flowing through said conversion zone, maintaining a temperature of about 850° to 950° F. and a hydrogen partial pressure of 75 to 200 p. s. i. in the resulting mixture of said product gas and said hydrocarbons, withdrawing said mixture from said conversion zone, and subsequently subjecting said mass which has been exposed to said mixture of said product gas and said hydrocarbons to contact with said regenerating gas and subjecting said mass which has been exposed to said regenerating gas to contact with said mixture of said product gas and said hydrocarbons.

7. The process of converting hydrocarbons by passage through a mass of catalyst wherein carbonaceous matter is deposited by said hydrocarbons during passage therethrough and said carbonaceous matter is subsequently removed by a regenerating gas, which comprises maintaining said mass at a pressure of about 300 to 650 p. s. i. g. in fluid-communicating conversion and regeneration zones, supplying to said mass in said regeneration zone a regenerating gas consisting essentially of steam and oxygen of at least about 90% by volume purity in the respective molar proportions of about 3:1 to 7:1 to effect removal of said carbonaceous matter by conversion at a temperature of about 1600° to 2500° F. to a regeneration product gas consisting predominantly of hydrogen and carbon monoxide, flowing said product gas through said mass in said conversion zone and simultaneously and continuously injecting said hydrocarbons into said product gas while said product gas is flowing through said conversion zone, maintaining a temperature of about 800° to 1050° F. and a hydrogen partial pressure of about 75 to 200 p. s. i. in the resulting mixture of said product gas and said hydrocarbons, withdrawing said mixture from said conversion zone, and subsequently subjecting said mass which has been exposed to said mixture of said product gas and said hydrocarbons to contact with said regenerating gas and subjecting said mass which has been exposed to said regenerating gas to contact with said mixture of said product gas and said hydrocarbons.

8. The process of converting heavy hydrocarbons of the type of topped petroleum crude oil by passage through a mass of catalyst wherein carbonaceous matter is deposited by said hydrocarbons during passage therethrough and said carbonaceous matter is subsequently removed by a regenerating gas, which comprises maintaining said mass at a pressure of about 200 to 800 p. s. i. g. in fluid-communicating conversion and regeneration zones, supplying to said mass in said regeneration zone a regenerating gas consisting essentially of steam and oxygen of at least about 90% by volume purity in the respective molar proportions of about 3:1 to 7:1 to effect removal of said carbonaceous matter by conversion at a temperature of about 1600° to 2500° F. to a regeneration product gas consisting predominantly of hydrogen and carbon monoxide, flowing said product gas through said mass in said conversion zone and simultaneously and continuously injecting said hydrocarbons into said product gas while said product gas is flowing through said conversion zone, maintaining a temperature of about 800° to 1050° F. and a hydrogen partial pressure of about 75 to 200 p. s. i. in the resulting mixture of said product gas and said hydrocarbons, withdrawing said mixture from said conversion zone, and subsequently subjecting said mass which has been exposed to said mixture of said product gas and said hydrocarbons to contact with said regenerating gas and subjecting said mass which has been exposed to said regenerating gas to contact with said mixture of said product gas and said hydrocarbons.
